TWISTING MACHINE

Frank P. A. Corda, North Tarrytown, N. Y.

Application February 13, 1943, Serial No. 475,817

1 Claim. (Cl. 57—25)

The present invention relates to new and useful improvements in twisting machines, and has for its primary object to provide, in a manner as hereinafter set forth, an apparatus of this character comprising a novel construction, combination and arrangement for separating the strands of a rope and twisting all of the separated strands simultaneously.

Another very important object of the invention is to provide a twisting machine of the aforementioned character which embodies unique means for maintaining the proper tension on the rope.

Other objects of the invention are to provide a twisting machine of the character described which will be comparatively simple in construction, strong, durable, highly efficient and reliable in use, and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in side elevation of a twisting apparatus constructed in accordance with the present invention.

Figure 2 is a view in front elevation of the twisting unit.

Figure 3 is a top plan view of the apparatus.

Figures 4 and 5 are cross sectional views, taken substantially on the line 4—4 and 5—5 of Figure 1.

Figure 6 is a view in longitudinal section, taken substantially on the line 6—6 of Figure 3.

Figure 7 is a view in longitudinal section, taken substantially on the line 7—7 of Figure 3.

Figure 8 is a view in vertical section through the twisting unit, taken substantially on the line 8—8 of Figure 1.

Figure 9 is a view in horizontal section through the rope anchoring swivel.

Referring now to the drawings in detail, it will be seen that the embodiment of the invention which has been illustrated comprises an elongated base which is designated generally by reference numeral 1. The base 1 includes a pair of spaced, parallel side bars 2 of suitable material having longitudinal channels 3 in their opposed sides. Rising from the forward end portion of the base 1 is a post 4 having a substantially T-shaped plate 5 mounted horizontally on its upper end.

Blocks 6 and 7 are operable longitudinally in the base 1 between the side bars 2, said blocks comprising, respectively, side flanges or tongues 8 and 9 which are slidably engaged in the channels or grooves 3. Rising from the block 6 is a pin or the like 10 to which a swivel 11 is connected. The swivel 11 constitutes means for anchoring one end of a length of rope, as at 12, to the block 6. A cable 13 has one end secured to the block 6. The cable 13 is trained around pulleys 14 on the members 4 and 5 and has suspended from its other end a weight 15 for moving the slideable block 6 in a direction to tension the rope 12.

Rising from the slideable block 7 is a fork 16 which is engageable between the strands 17 of the rope 12 for separating said strands. A cable 18 has one end connected to the block 7. The cable 18 is trained around pulleys 19 which are provided therefor on the base 1 and the member 5 and has its other end connected to a weight 20 which is slidably mounted on an inclined rail 21 which extends between said member 5 and said base 1. The cable 18 passes under the block 6.

Positioned adjacent the rear end of the base 1 is a twisting unit 22. The twisting unit 22 comprises an upstanding housing 23 having journaled therein a main shaft 24 and a plurality of countershafts 25, all of which shafts project from the front of the housing 23. The shaft 24 also projects rearwardly from the housing 23 and has fixed thereon a gear 26. A drive shaft 27 from any suitable source of power drives the gear 28 through a pinion 29. Gears 29 in the housing 23 connect the shafts 25 to the shaft 24 for actuation thereby. Hooks 30 are fixed on the forward ends of the shafts 24 and 25 for connecting the strands 17 of the rope 12 to said shafts.

It is thought that the operation of the apparatus will be readily apparent from a consideration of the foregoing. Briefly, one end of the rope 12 is connected to the swivel 11 on the block 6 and the strands 17 are separated at the other end of said rope and secured to the hooks 30. The fork 16 is then engaged between the separated rope strands. The shafts 24 and 25 are then rotated to twist the rope strands 17. As the strands 17 are twisted, the fork 16 is pulled toward the end of the rope 12 which is anchored to the block 6 for progressively separating said strands. As hereinbefore explained, the weight 15 maintains the proper tension on the rope 12.

It is believed that the many advantages of a twisting machine constructed in accordance with

the present invention will be readily understood, and although a preferred embodiment of the apparatus is as illustrated and described, it is to be understood that changes in the details of construction and in the combination and arrangement of parts may be resorted to which will fall within the scope of the invention as claimed.

What is claimed is:

A twisting machine of the character described comprising an elongated base including a pair of spaced, parallel side bars having longitudinal channels in their opposed sides, a pair of blocks operable between the side bars, said blocks in-

cluding tongues slidably engaged in the channels, means for connecting one end of a rope to one of the blocks, a fork on the other block engageable between the strands of the rope for separating said strands, a weight connected to said one block for tensioning the rope, a weight connected to said other block for moving the fork toward said one end of the rope for separating the strands, a housing, a plurality of shafts journaled in said housing, hooks on the shafts for connection with the rope strands for twisting same, and means for rotating the shafts.

FRANK P. A. CORDA.
